UNITED STATES PATENT OFFICE.

ORLANDO C. KETRING, OF PORTLAND, INDIANA.

WHEEL-ASSEMBLER.

1,080,638.

Specification of Letters Patent.

Patented Dec. 9, 1913.

Application filed September 4, 1912. Serial No. 718,596.

To all whom it may concern:

Be it known that I, ORLANDO C. KETRING, a citizen of the United States, residing at Portland, in the county of Jay and State of Indiana, have invented a new and useful 5 Wheel-Assembler, of which the following is a specification.

The present invention relates to a mechanism for assembling automobile and other 10 vehicle wheels.

It is the object of the present invention to provide a machine for conveniently and efficiently assembling the parts of an automobile wheel or the like by compressing the 15 various parts together.

The present invention also contemplates the provision of a machine of the character indicated embodying a bed plate on which the parts of the wheel may be assembled, the 20 bed plate having a circular series of independently and simultaneously actuating mechanisms thereon including radially movable wheel engaging shoes, so that the shoes may be moved inward simultaneously for 25 compressing the parts of the wheel into position.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

The invention has been illustrated in the accompanying drawings, wherein like reference characters have been employed to denote 40 corresponding parts, and wherein—

Figure 1 is a central vertical section of the machine, parts being removed. Fig. 2 is a plan view of the machine, parts being broken away and parts being removed. Fig. 45 3 is a sectional view of an operating valve employed in carrying out the invention. Fig. 4 is a sectional view taken on the line 4—4 of Fig. 3.

Referring specifically to the drawings, the 50 numeral 5 designates a circular face or bed plate having a central opening 6 to accommodate the hub of a wheel placed flatly on the plate and having a circular series of radial slots 7 therethrough, the said slots 55 forming slideways or guides. The bed plate 5 is mounted on the upper end of a hollow

pedestal 8, the upper end of the pedestal fitting around the opening 6 and being provided with a peripheral rabbet 9 under the bed plate. A plurality of legs 10 are also 60 provided for the bed plate, the same extending around the periphery of the bed plate at suitable intervals. A centering rod 11 is arranged axially within the pedestal 8 below the opening 6 and works through cross 65 pieces or guides 12 in the pedestal, said rod having a collar 13 designed to rest on the upper cross piece 12 in order to support the rod in its lowered position so that its upper end is dropped below the surface of the 70 bed plate 5. This rod 11 is reciprocated or elevated by means of a shaft 14 journaled through the pedestal 8 and having an arm 15 projecting therefrom connected to the rod 11 by a link 16. Thus, when the shaft 14 is 75 rocked, the arm 15 is oscillated so as to reciprocate the rod 11, and when the rod 11 is raised, the upper end thereof will project through the opening 6 and above the face of the bed plate 5 so that the hub of the wheel 80 to be assembled may be centered on the bed plate as will be apparent. This rod 11 may be normally retracted below the face of the bed plate by swinging the arm 15 downward.

A slide 17 is guided for reciprocatory 85 movement in each of the slots 7 flush with the upper face of the bed plate, the edges of the slides and slots having interengaging tongues and grooves. Each of the slides 17 is provided with a depending wrist pin 18 90 and a ring 19 is journaled for rotation upon the pedestal 8 within the rabbet 9, the said ring bearing against the bottom of the bed plate and having a peripheral series of depending wrist pins 20, the corresponding 95 wrist pins of the ring and slides being connected by pitmen 21. These pitmen 21 are arranged diagonally in order that the slides are constrained to reciprocate simultaneously and are connected to the lower faces 100 of the slides. An upstanding wheel engaging shoe 22 is detachably secured to and carried by the upper face of each slide 17, and a cylinder 23 is mounted on the bed plate at the outside of each shoe 22. A piston 24 is 105 provided in each cylinder 23 and has the piston rod 25 passing through the inner end of the corresponding cylinder and detachably secured to the corresponding shoe 22. Inasmuch as the slides 17 reciprocate 110 simultaneously, the pistons 24 will also reciprocate simultaneously, the pistons being

arranged in a series around the periphery of the bed plate and are also disposed radially of the bed plate, and the pistons being attached to the bed plate in any well known manner at the outer ends of the slots 7.

Each cylinder 23 is provided with a port 26 at its inner end and with a port 27 at its outer end, to which ports are connected the respective branch pipes 28 and 29, the inner 10 pipes 28 passing through the slots 7 adjacent their outer ends and the outer pipes 29 depending around the periphery of the bed plate. A concentric pair of circular pipes 30 and 31 are mounted or hung below the 15 periphery of the bed plate, said pipes being arranged on the inner and outer faces of the legs 10, respectively, as is preferable, and the respective branch pipes 28 and 29 are connected to the pipes 30 and 31.

20 By supplying steam, compressed air, or other fluid to one of the pipes 30 or 31, it will appear that the pistons of the various cylinders will be simultaneously moved in one direction, and that by admitting the 25 fluid to the other pipe, the pistons will be forced in the other direction. As a means for accomplishing this result, a device has 30 been provided as illustrated in Fig. 3. This device embodies a body 32 having a steam chest 33 secured thereto, the usual slide valve 34 working in the steam chest 33 to alternately admit steam or other fluid into the central chamber 36 in the body 32 and the annular chamber 35 in the body and to 35 reversely connect the said chambers with the exhaust port, as is well known in the art. The body 32 is provided with a port 38 leading to the chamber 36 and with a second port 37 leading to the chamber 35, so that 40 the pipes 30 and 31 may be connected to the respective ports, the chest 33 being connected to a suitable source of steam, compressed air or other fluid by means of a pipe 39. Thus, when the slide valve 34 is moved in one direction, the fluid will be admitted into one 45 of the pipes 30 or 31 so that the pistons will be forced in one direction, the other pipe being connected to the exhaust port, and when the slide valve is reversed, the reverse 50 operation will ensue.

In practice, the wheel to be assembled is placed on the bed plate within the shoes 22, the centering of the wheel being facilitated by the rod 11 on which the hub of the wheel 55 may be engaged. When the wheel has thus been assembled, steam or other fluid is admitted into the pipe 31 so that steam is supplied simultaneously to the outer ends of all of the cylinders 23 which causes the shoes 60 to be forced radially inward so as to compress the parts of the wheel together. The shoes 22 being made to move simultaneously will cause the parts of the wheel to be com-

pressed together evenly and with precision, and it will be noted that the cylinders 23 in 65 being arranged outside of the shoes 22 will cause the shoes to be forced inwardly with great pressure. When the wheel has then assembled, the shoes 22 may be moved outwardly, by reversing the steam supply, that 70 is, by permitting the steam to enter the pipe 30 and by connecting the pipe 31 with the exhaust port.

From the foregoing, taken in connection with the drawings, the advantages and capabilities of the present invention will be apparent and it will be observed that the objects aimed at have been carried out in a satisfactory manner, the present device providing a desirable one for the purposes for 80 which it is designed.

If desired, a second ring 19 may be journaled for rotation upon the pedestal 8 and may be connected by pitmen to the slides 17 so as to rotate in a direction opposite to the 85 rotation of the aforesaid ring. The employment of two rings 19 will obviate any side draft on the slides which carry the wheel engaging shoes.

Having thus described the invention, what 90 is claimed as new is:—

1. A wheel assembler embodying a bed plate having a central opening and a series of radial slots therethrough, a hollow pedestal supporting the bed plate, slides working 95 in the slots, upstanding wheel engaging shoes carried by the slides, a ring mounted to rotate on the pedestal below the bed plate, pitmen connecting the ring and lower faces of the slides, and simultaneously operable independent mechanisms mounted on the bed plate around the shoes and connected thereto for operating them.

2. A wheel assembler embodying a bed plate having a central opening and a series 105 of radial slots therethrough, slides working in the slots flush with the upper face of the bed plate, the edges of the slides and slots having interengaging tongues and grooves, upstanding wheel engaging shoes detachably 110 secured to the upper faces of the slides, a member rotatable below the bed plate, pitmen connecting the rotatable member and the lower faces of the slides, a series of fluid pressure cylinders mounted on the bed plate 115 around the shoes, and pitmen working in the cylinders and having piston rods projecting inwardly and detachably connected to the respective shoes.

In testimony that I claim the foregoing as 120 my own, I have hereto affixed my signature in the presence of two witnesses.

ORLANDO C. KETRING.
